UNITED STATES PATENT OFFICE.

ADOLPH WUNDER, OF NEW HAVEN, CONNECTICUT, ASSIGNOR TO SARGENT & CO., OF SAME PLACE.

DESIGN FOR FIRE-IRON STANDS.

Specification forming part of Design No. 5,286, dated September 26, 1871.

To all whom it may concern:

Be it known that I, ADOLPH WUNDER, of the city and county of New Haven and State of Connecticut, have invented a new and original Design for Fire-Iron Stand; and I do hereby declare the following, when taken in connection with the accompanying drawing and the letters of reference marked thereon, to be a full, clear, and exact description, and which said drawing constitutes part of this specification, and represents a perspective view.

This invention relates to a design for the article of household use commonly called fire-iron stand, designed to support the shovel, tongs, &c., used about the fire; and the invention consists in the peculiar configuration of the post, the pan, and arms, constituting a part of a design for which I have filed application for patent in even date herewith.

The post extends upward from the pan to support the arms, and is of the form shown in the accompanying illustration.

I claim—

The design for fire-iron stand, described and shown in the accompanying illustration.

ADOLPH WUNDER.
